UNITED STATES PATENT OFFICE.

HENRY JOHNSON, OF WASHINGTON, DISTRICT OF COLUMBIA.

BILL-FILE.

SPECIFICATION forming part of Letters Patent No. 417,043, dated December 10, 1889.

Application filed October 17, 1889. Serial No. 327,312. (No model.)

To all whom it may concern:

Be it known that I, HENRY JOHNSON, a citizen of the United States, and a resident of Washington, in the District of Columbia, have 5 invented a new and useful Improvement in Bill-Files, of which the following is a specification.

This invention relates to that class of "bill-files" in which the bills or other papers are 10 impaled upon and suspended in bundles by suitable hooks.

The primary object of my present invention is to provide for employing any required 15 number of such hooks in "individual files" so supported by a "cabinet" or index-frame common to all as to facilitate keeping the papers in chronological or alphabetical order or classified according to subject-matter, and thus facilitate finding any desired paper.

Another object of the invention is to adapt 20 detachable individual files to coact with an index-frame of simple construction, so that the hooks shall project uniformly at right angles to the front of the frame when the 25 files are hung up in place.

Another object is to provide for using an attached unfile-wire for exposing individual papers with superior facility.

Another object is to facilitate tying up the 30 papers in their original order when they are removed from the hooks; and a last object is to provide for packing the individual files flat, so as to economize space in storing and shipping them.

This invention consists in certain novel 35 combinations of parts for effecting the above objects, as hereinafter described and claimed.

Two sheets of drawings accompany this specification as part thereof.

Figure 1 of the drawings represents a face view of a "horizontal" chronologically-indexed bill-file embodying all the several features of this invention. Fig. 2 is a like view of a "classified" horizontal file illustrating 45 certain modifications. Fig. 3 is a like view of a horizontal alphabetically-indexed file illustrating additional modifications. Fig. 4 is a like view of a vertical file illustrating additional modifications. Fig. 5 represents a 50 section on the line 5 5, Fig. 1, enlarged therefrom four diameters, and illustrating by full and dotted lines the operation of the indi-

vidual file in the plane of section. Fig. 6 is a face view of this individual file on the same scale as Fig. 5. Fig. 7 is a small scale 55 side view of the impaling-hook detached, illustrating the chronological subdivision of bundles of papers and the provision for tying up the papers, and Fig. 8 is a face view of the individual file as flattened for storage or 60 shipment.

Like letters of reference indicate corresponding parts in the several figures.

My cabinets or index-frames I I² I³ I⁴ have in common one or more pairs of horizontal bars a b, rigidly united by vertical cross-bars c. The upper bars a are provided with suspending devices, which may be L-shaped hooks d, Figs. 1, 2, 4, and 5, or headed nails or the like, as shown at d², Fig. 3. In 70 either case they are arranged in series, and index-marks or labels e are affixed to said bars a or to adjoining parts of the frame adjacent to the respective suspending devices. Other portions of the frames may be utilized for labels e², Fig. 1, bearing directions, advertisements, or the like.

Each individual file F, or F², or F³, or F⁴ has an eye f at the upper end of its body, to engage with one of the suspending devices d 80 or d², and may have a mark e' corresponding with the index-mark e appropriate to that particular hook or nail, and lateral projections g, horizontally opposite each other at the lower end of the body of the file, coact with 85 the frame-bar b, against which the individual file hangs. The impaling-hook h of the file is thus caused to project at right angles to the face of the frame, being set in a plane at right angles to the back of the file. The bars 90 b of the several index-frames are fixedly located with reference to the above function. The bodies of the individual files are conveniently adapted therefor by being made of anchor shape, as shown at F and F², or in the 95 shape of T-squares, as shown at F³ and F⁴. Other analogous shapes may be adopted.

The index-frames may be extended horizontally or vertically to any required length, as illustrated by Figs. 1 to 4, and may be fixedly attached to an office-wall, the inner side of a closet-door, or a like support, as by screws i, Figs. 1 and 5, or be detachably hung on nails j, or the like, with or without eye-screws

k or holes *l* to engage therewith, as illustrated by Figs. 2 to 4.

In the specific construction of individual files illustrated by Fig. 1 and by Figs. 5 to 8 each file-body is provided with a vertical screw-socket *m*, Figs. 5 to 8, opening upward, and a recurved elastic unfiling-wire *n* has a screw-threaded heel end fitted to the sockets *m*, so that it may be quickly attached to any file of the series when it is needed, and when it is not in use may be swung back out of the way, as shown in Figs. 1 and 6. The free end of the unfiling-wire is constructed with a longitudinal socket, which admits the sharp end of the impaling-hook of the file, to which it is attached, as shown in dotted lines at *n* in Fig. 5, so that the papers may be turned back from the hook *h* onto the wire *n* in removing or exposing to view an individual paper. In connection with such single unfiling-wire to a series of files a detent-hook *o* preferably forms part of each individual file for ordinary use as the keeper of the free end of the impaling-hook, as shown in Figs. 1 and 25 6 and in full lines in Fig. 5.

To provide for transferring the bundles of papers to strings *S*, Fig. 7, the impaling-hook *h* is made detachable by being screwed into a vertical screw-socket *m*², opening downward at the lower end of the file-body, and is provided at the extremity of its screw-threaded end with an eye *p*, Figs. 5 and 7, which is readily threaded with the string after the hook is detached, as illustrated by Fig. 7. 35 The papers may then be slipped from the hook onto the string without changing their order and secured against disarrangement by tying the string. The hook is then returned to the file to which it belongs. Fig. 7 further illustrates subdividing the papers *P* on a given impaling-hook by means of cards or tags *q* representing successive dates. For druggists, coal-dealers, and others handling a large number of papers of uniform size this provision is of 40 great practical importance, as it provides for turning to papers of any given date on an impaling-hook which answers for one or more months or for all current bills or the like of a given initial or class. The improved bill-50 file may be adapted in like manner for the peculiar demands of any other business.

By providing a screw-socket *m*³ perpendicular to the back of the file-body for the detent-hook *o*, when the latter is employed, and unscrewing the detent-hook and partly unscrewing the unfiling-wire *n* and the impaling-hook *h*, the file may be flattened, as shown in Fig. 8, and packed in this shape for storage or shipment without the large loss of space 60 which has heretofore militated against commercially handling bill or paper files of said impaling-hook type. The modified individual files *F*² and *F*³, Figs. 2 and 3, are made without the said detent-hook *o* and its socket *m*³, the unfiling-wire *n* being employed on each file as a combined detent and unfiling device, and the eye *f* of said file *F*³ is made

in the form of a key-hole slot suited to the suspending devices *d*². Otherwise they are constructed as above described.

The modified individual files represented at *F*⁴, Fig. 4, are made without said unfiling-wire *n*, and the index-frame *I*⁴, used in connection therewith, is provided with means represented by vertical holes at *r*, Fig. 4, whereby a detached unfiling-wire *n*² is conveniently held by the frame so as to be used in connection with either file for unfiling purposes. 75

Having thus described the said improvement and modification thereof, I claim as my invention and desire to patent under this specification—

1. An index-frame provided with a series of suspending devices and index marks or labels adjacent to the respective suspending devices, in combination with a series of individual files having impaling-hooks to hold the papers, eyes to engage with said suspending devices, and marks or labels corresponding with those on the index-frame, substantially as hereinbefore specified. 85

2. An index-frame having a pair of horizontal bars, the upper provided with suspending devices, in combination with a series of individual files, each having an impaling-hook 95 to hold the papers, and a body having an eye at its upper end to engage with one of said suspending devices, and lateral projections at its lower end to engage with the lower bar of said pair, substantially as hereinbefore 100 specified.

3. An index-frame provided with a series of suspending devices and index marks or labels adjacent to them, respectively, in combination with a like series of individual files, 105 each having an impaling-hook to hold the papers, and a body having an eye at its upper end to engage with one of said suspending devices, and a vertical screw-socket opening upward, and an elastic rebent unfiling-wire, 110 having a screw-threaded end adapted to screw into such socket of any file of the series, and a hollow end to receive the sharp end of the impaling-hook of the file to which it is attached, substantially as hereinbefore specified. 115

4. In a bill-file, the combination of an impaling-hook having an upwardly-projecting sharp end, a body having a vertical screw-socket opening upward, and an elastic rebent 120 unfiling-wire having a screw-threaded end fitted to said socket, and a hollow end to receive said sharp end of the impaling-hook, substantially as hereinbefore specified.

5. In an individual file, a detachable impaling-hook having one end sharpened and its other end screw-threaded and provided with a terminal eye, in combination with a body having a downwardly-opening vertical socket at its lower end to receive said eye end of the hook, substantially as hereinbefore specified. 125

6. An individual file having its body constructed with an eye at its upper end, by which to suspend the file, and with vertical

screw-sockets opening downward and upward, respectively, and having an impaling-hook and an unfiling-wire constructed with screw-threaded heel ends fitted to the respective 5 sockets, substantially as hereinbefore specified.

7. The combination, in an individual file, of a body constructed with an eye at its upper end by which to suspend the file, and 10 with screw-sockets, two of which are vertical

and open downward and upward, respectively, and the third is at right angles to the back of the file, an impaling-hook, and an unfiling-wire screwed into said vertical sockets, and a detent-hook screwed into said third socket, 15 substantially as hereinbefore specified.

HENRY JOHNSON.
